Specification for Design.

Patented June 4, 1918.

Application filed March 28, 1918. Serial No. 225,360. Term of patent 3½ years.

To all whom it may concern:

Be it known that I, NATHAN ROSEN, a citizen of the United States, and a resident of New York, in the county of New York and State of New York, have invented a new, original, and ornamental Design for a Lamp-Hood, of which the following is a specification, reference being had to the accompanying drawing, forming a part thereof.

In the drawing, the figure is a perspective view of a lamp hood, embodying my ornamental design.

Copies of this patent may be obtained for five cents each, by addressing the "Commissioner of Patents, Washington, D. C."

I claim:—

The ornamental design for a lamp hood as shown.

This specification signed and witnessed this 27th day of March A. D. 1918.

NATHAN ROSEN.
